United States Patent Office

Des. 227,333

Patented June 19, 1973

227,333

SKILLET OR SIMILAR ARTICLE

John Di Lorenzo, 235 W. 46th St.,
New York, N.Y. 10036

Filed Feb. 1, 1972, Ser. No. 222,717

Term of patent 3½ years

Int. Cl. D7—02

U.S. Cl. D7—85

FIG.1

FIG. 4

FIG. 1 is a top perspective view of a skillet or similar article showing my new design;

FIG. 2 is a bottom plan view thereof;

FIG. 3 is an elevational view of the side opposite that shown in FIG. 1; and

FIG. 4 is an end elevational view thereof as seen from the left of FIG. 3.

I claim:

The ornamental design for a skillet or similar article, substantially as shown.
